UNITED STATES PATENT OFFICE.

CLEM G. MOORE, OF CRAWFORDVILLE, GEORGIA.

DESIGN FOR A CUTTER AND CLEANER FOR GREEN CORN.

SPECIFICATION forming part of Design No. 32,786, dated June 5, 1900.

Application filed May 3, 1900. Serial No. 15,416. Term of patent 34 years.

To all whom it may concern:

Be it known that I, CLEM G. MOORE, a citizen of the United States, residing at Crawfordville, in the county of Taliaferro and State of Georgia, have invented and produced a certain new and original Design for a Cutter and Cleaner for Green Corn; and I do declare the following to be a full, clear, and exact description of the invention, such as will enable others skilled in the art to which it appertains to make and use the same.

The invention relates to a new and original design for a cutter and cleaner for green corn to be used in pulling the husks from the corn, brushing the silk from the crevices between the rows, gouging out worm-eaten places, and cutting the corn from the cob.

In the accompanying drawings, Figure 1 is a perspective view of my design. Fig. 2 is a

longitudinal sectional view, and Fig. 3 is a cross-sectional view.

The leading feature of the design comprises a hollow shell 1, the ends of which taper in opposite directions and one end of which is provided with cutting edges 2, a tapering point 3, and a cutter 4, while the other is provided with a brush-stock 5.

What I claim is—

The design for a cutter and cleaner for green corn, as herein shown and described.

In testimony whereof I have hereunto set my hand in presence of two subscribing witnesses.

CLEM G. MOORE.

Witnesses:

EDMUND GOLUCKE,
R. H. RHODES.
